FUSE

Charles C. Lauritsen, Pasadena, Calif., assignor to
the United States of America as represented by
the Secretary of the Navy

Application April 2, 1943, Serial No. 481,647

1. Claim: (Cl. 102—76)

12

This invention relates to fuses and more particularly to a spring-armed, impact-fired, nose fuze of novel construction which is positive and reliable in operation and may be handled with safety. By reason of its spring arming, the new fuze may be used to particular advantage in rocket-propelled projectiles, and the like, where, in setback forces alone are too small to be employed safely for arming, and centrifugal forces for arming are lacking.

One object of the present invention resides in the provision of a novel spring-armed fuze, including safety means for locking the spring and operable jointly by setback and by actuation of an arming wire to release the spring and permit arming of the fuze.

Another object of the invention is to provide a spring-armed fuze of novel construction having a firing pin movable by the spring from a safe position to an armed position, and a releasable nose cap on the fuze serving the dual function of shielding part of the firing pin and locking the pin against movement to its armed position.

A further object of the invention is to provide a fuze of the character described in which the nose cap is released by actuation of the arming wire, so that the safety means may be rendered inoperative in response to a force of setback.

These and other objects of the invention may be better understood by reference to the accompanying drawing, showing one form of the new fuze in longitudinal sectional view.

Referring to the drawing, the fuze there shown is adapted for use in vertically-dropped airplane bombs of the type which is projected rearwardly from the airplane by a rocket motor, whereby the bomb strikes a point substantially in line vertically with the point of release of the bomb from the airplane.

The fuze comprises a generally cylindrical casing 10 which is externally threaded near its rear end, as shown at 11, so that the casing may be screwed into a suitable receptacle in the nose of the bomb (not shown). Threaded in the rear end of the casing is a container 12 adapted to receive the usual booster charge for detonating the main charge in the bomb. The front end of the booster container 12 is closed by a plate 13 in the casing having a central opening 14 communicating with the booster charge. A liner 15 in the casing abuts at one end against the plate 13 and at the opposite end against a disc 16 seated against a shoulder in the casing, the liner, disc and plate defining a chamber 15a.

A safety gate 18 is mounted in chamber 15a on

5 a pivot 19 and is adapted to swing transversely in the chamber on the pivot. The safety gate is provided with a recess 20 into which the rear end of a firing pin 21 normally extends, the firing pin projecting through the disc 16 in which it is threaded. The gate 18 is biased against one side of the firing pin by a spring 22 mounted in a retainer 23 in the gate. A suitable semi-cap (not shown) is held in the safety gate in offset relation to the recess 20 and the firing pin, and when 10 the firing pin is withdrawn from recess 20, the gate is moved by the spring 22 to an armed position in which the semi-cap is aligned with the firing pin and the opening 14. Thus, in the armed 15 position of the safety gate, rearward movement of the firing pin 21 explodes the semi-cap and detonates the booster through opening 14.

A flywheel 25 in the form of a sleeve is mounted on the firing pin in front of disc 16, the sleeve being keyed to the firing pin by a key 26 engaged in a longitudinal slot in the sleeve. A helical driving spring 27 is coiled around the sleeve between the disc 16 and a flange 28 on the sleeve, the inner end of the spring being connected to the sleeve and the outer end being anchored in the casing by a pin 29. Slidably mounted on the sleeve 25 is a set-back pellet or collar 30 which is keyed to the sleeve by a key 31. The pellet 30 is urged forwardly against a stop 32 on the firing pin by a compression spring 33 coiled around the sleeve 25 and seated at one end against flange 28 and at the opposite end against the pellet. It will be understood that the firing pin, the sleeve 25 and the setback pellet rotate as a unit and that the firing pin and pellet are movable longitudinally with respect to the sleeve 25.

The front end of the casing 10 is closed by a plug 34 which contains a plunger 35 slidable transversely of the casing. A locking detent 36 on the plunger extends rearwardly through a slot in the plug 34 and into a recess in pellet 30. The plunger 35 is urged outwardly in the plug by a compression spring 37 but is locked against the spring by a pin 38 movable transversely of the plunger and projecting through the front face of the plug. The pin 38 is normally held in its locking position by a cap 39 on the nose of the fuze casing, the cap being locked on the casing against the action of one or more springs 40 compressed between the cap and the front face of plug 34.

The cap 39 is held against a sealing gasket 42 on the casing by locking means which, as shown, comprises a ring 43 extending around the casing 55 in contact with the edge portion of the cap which

is turned outwardly, the ring being made in two or more sections movable radially outwardly to release the cap. An expansible spring 44 extends around the casing inside the ring 43 and acts to separate the sections of the ring, which are held in their locking positions against the spring 44 by an expansible band 45 extending around the outside of the ring. The band 45 comprises two semi-circular sections pivoted at adjacent ends, as shown at 45a, and held together at their opposite ends by outwardly extending tabs 46. A headed pin 47 extends through the tabs 46 which are clamped together by a safety wire 48 extending transversely through the pin, the wire being formed with a loop 48a which serves as a handle for withdrawing the wire from the pin, thereby releasing the band 45. When the bomb is mounted on an airplane, an arming wire 49 is inserted through the pin 47 to hold the band sections 45 together, and the safety wire 48 is removed. A washer 50 may be inserted between the head of the pin 47 and the wire 48.

The front end of the firing pin 21 projects through plug 34 into the cap 39. Within the cap is a cross piece 52 keyed to the firing pin and having laterally extending fingers engaging the locking pin and spring assembly 38-40, so that the latter prevents accidental rotation of the firing pin when the fuze is being handled. Thus, when the fuze is not in use, the firing pin is locked in its safe position by the locking pin and spring assembly 38-40 and by the set-back collar 33 and detent 36. Also, the gate 18 is held in its safe position by the rear end portion of the firing pin.

The operation of the fuze is as follows: When the bomb is projected from an airplane, the arming wire 49 is withdrawn from pin 47 to release the band 45 and the ring 43. As a result, the sections of ring 43 are moved outwardly by spring 44 so as to disengage and release the nose cap 39, and the latter is forced away from the fuze casing by springs 40, thereby removing locking pin 38 and releasing cross-piece 52 on the firing pin. At the same time, the set-back pellet 30 moves rearwardly against spring 33 under the force of set-back incident to acceleration of the bomb by the rocket motor, whereby the set-back pellet disengages the locking detent 36. The spring 37 then moves the detent 36 outwardly on plunger 35, which has been released by the locking pin 38. Accordingly, when pellet 30 is moved forwardly against plug 34 after the force of set-back is dissipated, the detent 36 engages only the peripheral portion of the pellet and cannot lock the pellet against rotation.

The firing pin 21 is now released and is rotated by spring 27 in the sleeve 25, whereby the firing pin is screwed forwardly in the plate 16 and the sleeve so that the rear end portion of the firing pin is withdrawn from gate opening 20. The gate 18 is then moved by spring 22 to its armed position to aline the semi-cap (not shown) with the firing pin and the discharge opening 14. When the bomb strikes a target, the impact on

the exposed cross-piece 52 forces the firing pin to the rear against the semi-cap in gate 18, shearing the threads in plate 16. The semi-cap, therefore, is fired and acts through opening 14 to detonate the booster charge in container 12. It will be apparent that when the firing pin is screwed to its armed position by spring 27, contact between any part of cross-piece 52 and the target actuates the firing pin to explode the semi-cap.

I claim:

A fuze comprising a casing, a flywheel in the casing, a firing pin threaded in the casing and extending through the flywheel, the pin being rotatable with the flywheel and movable endwise therein, a driving spring coiled around the firing pin for rotating the flywheel to screw the pin from a safe to an armed position, a setback collar on the firing pin rotatable with the pin and movable endwise thereon, a detent engageable in an opening in the collar to lock the pin against rotation, biasing means for urging the collar into locking relation with the detent, the collar being movable against the biasing means by a force of setback to disengage the detent from said opening and release the firing pin, actuating means for moving the detent to an inoperative position wherein the collar and the firing pin are free to rotate, said last means being inoperative when the detent is in said opening, a locking member normally securing the detent against movement by said actuating means and urged toward an inoperative position, a laterally extending element on one end of the firing pin and operable upon impact with a target to actuate the pin for firing the fuze, said element being engageable with the locking member to secure the firing pin against rotation, a cap on the casing for shielding said element and holding said member in its locking position, and means including an arming wire for securing the cap on the casing and operable by actuation of the wire to release the cap and said locking member.

CHARLES C. LAURITSEN.
